James Kershaw,
By James L. Morris, Attorney.

UNITED STATES PATENT OFFICE.

JAMES KERSHAW, OF LONDON, ENGLAND.

SPRING BUTTON-FASTENER FOR GLOVES, &c.

SPECIFICATION forming part of Letters Patent No. 417,191, dated December 10, 1889.

Application filed July 10, 1889. Serial No. 317,015. (No model.) Patented in England May 22, 1889, No. 8,490.

To all whom it may concern:

Be it known that I, JAMES KERSHAW, a subject of the Queen of Great Britain, residing at 97 Wood Street, in the city of London, 3 England, have invented an Improved Construction of Spring Button-Fasteners for Gloves, Boots, Purses, Pocket-Books, Umbrellas, and other Articles, (patented in Great Britain, No. 8,490, dated May 22, 1889,) of which 10 the following is a specification.

The object of this invention is a novel construction of spring button-fasteners for gloves, boots, and other articles, and belongs to that class or description of fasteners, brought into 15 use within the last few years, which have the advantage of dispensing with the button-hole, and it is based on the principle of a split spherical button capable of being contracted while being pushed into an eyelet, and held 20 therein by reason of its expansive action when forced far enough into the eyelet.

My invention consists, essentially, in a button-fastening comprising a plate having two base-wings and two other wings bent up 25 toward each other and provided with spherical protuberances, a base-plate having a conical or cone ring and an eyelet for clamping the conical or cone ring and the said base-wings to a glove, shoe, or other article, as 30 more fully described hereinafter, reference being made to the accompanying drawings, in which—

Figure 1 is a sectional view of the button-fastener. Fig. 2 is a detail plan view of the 35 plate to comprise the button-head. Fig. 3 is a sectional view of the same. Fig. 4 is a side elevation of the same, showing the wings bent to form the spherical head. Fig. 5 is a top plan view of the same. Fig. 6 is a side elevation of the eyelet for securing the button-head and the base-plate to the glove or other object. Fig. 7 is a side elevation of the button-head and base-plate united together. Fig. 8 is a top plan view of the same. Fig. 9 45 is a side elevation of the socket with which the button-head engages; Fig. 10, a bottom plan view of the same, and Fig. 11 is a detail side view of the eyelet section of the socket.

In the drawings, as shown, the button-head 50 proper is made from a plate of metal, com-

prising four wings, two base-wings *b b*, and two other wings *a a*, all cut or stamped out of sheet metal, the wings *a* being formed with spherical protuberances. The two parts *a a* are then bent upward, as at Figs. 4 and 5, and 55 the two wings *b b* and their connecting portion arched, as shown in the elevation, Fig. 4. The piece of metal thus prepared has its wings *b b* inserted into its base *c*, and when it has to be fixed to the glove or other article a cone 60 ring or washer *c'* is inserted into the base, and then an eyelet *d* is passed through a hole in the leather to which this part of the button has to be attached, the flange of the eyelet and the cone-washer *c'* being pressed into the 65 leather of the glove or other article which is between them. This pressure tends to spread out the lower flange *d'* of the eyelet *d* (see Fig. 6) against the cone-washer *c'*, to lock 70 the parts and the leather firmly together. 70

Figs. 7 and 8 show in elevation and in plan the button placed temporarily in its base. It then only requires the eyelet which is to connect them permanently and the cone-washer *c'*, to affix them to the glove or other article 75 75 by the aid of a suitable tool, not necessary to herein exhibit.

The socket is composed of a cap *k*, (shown separately in elevation, Fig. 9,) inclosing a washer *m* and a gutter-shaped ring *n*, in which 80 cap, at the time of affixing the socket, the eyelet *l* is inserted, (shown in Figs. 10 and 11,) this eyelet resting against the washer *m*, (shown in the section, Fig. 1,) and with its flange against the leather, to which it is attached by pressure. The object of inserting the washer *m* between the cap and the eyelet 85 is not only to strengthen or consolidate the socket, but also to exert a tightening action, which insures the nip and hold on the button 90 in spite of the movements of the wrist tending to force the button and cap apart and unfasten them.

I am aware that split and other shaped bulbs or spheres have been used as part of a 95 glove or like fastener; but these have been made with a flange for sewing or riveting directly onto the glove or other article; therefore I make no claim to the use of such spheres, except when the wings *b* are arched and em- 100

ployed in combination with the base *c*, cone-washer *c'*, and eyelet *d*, for the purpose described.

I claim—

- 5 A member of a button-fastening, comprising the plate having base-wings *b* and two wings *a*, bent up toward each other and provided with spherical protuberances, the base-plate *c*, having the cone-ring *c'*, and the eyelet *d*, for clamping the cone-ring and base-wings to the glove or other article, substantially as described.

In witness whereof I have hereto signed my name, in the presence of two subscribing witnesses, this 29th day of May, 1889.

JAMES KERSHAW.
